FOREIGN PATENT DOCUMENTS

CN 302534790 S 8/2013

Primary Examiner — Cynthia M Chin(74) *Attorney, Agent, or Firm* — Muncy, Geissler, Olds & Lowe, P.C.(57) **CLAIM**

The ornamental design for a human-machine interaction vehicle, as shown and described.

DESCRIPTION

FIG. 1 is a top plan view of a human-machine interaction vehicle showing my new design;

FIG. 2 is a bottom plan view thereof;

FIG. 3 is a front elevational view thereof;

FIG. 4 is a rear elevational view thereof;

FIG. 5 is a right side view thereof;

FIG. 6 is a left side view thereof; and,

FIG. 7 is a top, rear, right perspective view thereof.

The broken lines are for the purpose of illustrating portions of the human-machine interaction vehicle and environmental structure which form no part of the claimed design.

1 Claim, 7 Drawing Sheets(56)
